[57] CLAIM

The ornamental design for a shower ring, as shown and described.

DESCRIPTION

FIG. 1 is a front perspective view of a shower ring showing my new design, the woman shown in broken lines is for illustrative purposes only and forms no part of the claimed design;

FIG. 2 is a top plan view thereof;

FIG. 3 is a bottom plan view thereof; and

FIG. 4 is a side elevational view thereof.

The broken lines on the shower ring shown in FIGS. 1-3 are understood to represent conventional stitching.

FIG. 3

FIG. 4
